(57) **CLAIM**

The ornamental design for a plaque for displaying a patent, as shown and described herein.

DESCRIPTION

FIG. 1 is a perspective top view of a new design for a plaque for displaying a patent, according to our new design; FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

Broken lines are used to illustrate features of the plaque for displaying a patent that form no part of the claimed design.
